Specification for Design.

Patented May 10, 1921.

Application filed August 16, 1920. Serial No. 403,960. Term of patent 14 years.

To all whom it may concern:

Be it known that I, HARRY O. BARTLETT, a citizen of the United States, residing at Washington, in the District of Columbia, have invented a new, original, and ornamental Design for a Gear-Casing for Washing-Machines, of which the following is a specification, reference being had to the accompanying drawings, forming a part thereof.

Figure 1 is a perspective view of a gear casing for washing machines embodying my invention.

Fig. 2 is a plan view of the same, and,
Fig. 3 is a side elevation of the same.

I claim:

The ornamental design for a gear casing for washing machines, as shown.

HARRY O. BARTLETT.
